INVENTOR.

PHILIP A. WOOSTER,
By *Arthur L. Sloo.*
HIS ATTORNEY.

UNITED STATES PATENT OFFICE

PHILIP A. WOOSTER, OF SAN FRANCISCO, CALIFORNIA

DISPENSING DEVICE

Application filed September 30, 1931. Serial No. 588,057.

My invention relates to improvements in dispensing devices, and particularly of the type used for dispensing powdered soap wherein the outlet and dispensing passages are rendered accessible for cleansing purposes to dislodge accumulations of powdered soap which might tend to prevent a proper operation of the device.

Devices of this type, including, in combination, a receptacle having a reciprocating valve movable to dispense a predetermined quantity of soap or other commodity, are common, and one of the objects of the present invention is to improve upon the construction and arrangement of such devices to the end that the passages may be easily rendered accessible for cleansing purposes and to remove any accumulation of soap or other commodity which may interfere with the proper operation of the device.

A still further object is to provide a new and improved soap dispensing device wherein the soap being dispensed will be discharged vertically between vertical walls, while falling freely, through the action of gravity, to prevent, as far as possible, the accumulation of a dispensed commodity within the discharge passages.

I accomplish these and other objects by means of the improved device disclosed in the drawing forming a part of the present application, wherein like characters of reference are used to designate similar parts throughout the specification and drawing, and in which—

Fig. 1 is a side elevation, partly in vertical section, disclosing my improved dispensing device;

Fig. 2 is a transverse sectional view taken on line 2—2 of Fig. 1 in the direction indicated; and

Fig. 3 is a broken plan view disclosing the dispensing passage.

The invention comprises a receptacle 1, for containing a commodity to be dispensed, such

as powdered or flake soap, and has its upper and lower ends opened. The upper end is closed by means of any suitable cap 2, while the lower end is threaded or otherwise secured to a housing 3, said housing 3 being provided with a chamber 4 directly below and communicating with the bottom opening of the receptacle 1, said chamber 4 in turn being provided with a vertically disposed dispensing passage 6 whose lower end 7 is normally closed with a suitable plug 8.

A valve casing 9 intersects the passage 6 and is provided with a vertically disposed outlet 11, preferably parallel with and offset from the passage 6, the purpose of which will hereinafter be more fully set forth.

Slidably mounted for reciprocal or longitudinal movement within the valve casing 9 I have provided a valve 12 held against rotation within said valve casing by means of a suitable screw 14 mounted within the housing 3 and engaging a longitudinally disposed slot or groove 16 within said valve 12, as disclosed in Figs. 1 and 2 of the drawing.

The valve 12 is also provided with a vertically disposed lateral dispensing aperture 17 intermediate the ends thereof, said aperture 17 being arranged to register with either the discharge passage 6 or the outlet 11 of the valve casing 9, but a spring 18 is interposed between the inner end of the valve 12 and the casing 9 and is arranged to normally urge the valve 12 outwardly from said casing to register the aperture 17 with the discharge passage 6, said outward movement being adjustably limited by means of a screw-threaded cap 21 through which projects a suitable stem 22 by means of which said valve 12 may be moved, against the tension of the spring 18, to register the aperture 17 therein with the outlet 11 of the valve casing 9, when it is desired to dispense a predetermined quantity of soap, said quantity being predetermined by the capacity of the dispensing aperture 17.

In operation, the receptacle 1 is filled with

dry, powdered soap, or the like, which readily flows into the chamber 4 and a predetermined quantity of said soap flows into and fills the dispensing aperture 17 of the valve 12.

When it is desired to dispense this predetermined quantity the valve 12 is moved to its extreme inward position, by means of the exteriorly extending stem 22, against the tension of the spring 18, in which position the dispensing aperture 17 of the valve 12 will register with the outlet 11 when the quantity of soap within said aperture 17 will be dispensed, by the action of gravity, through said outlet 11.

When the stem 22 is released the spring 18 will urge the valve 12 to its outermost position with the aperture 17 in registration with the discharge passage 6, when it will again be filled, ready for the next operation.

The vertically disposed outlet 11 provides accessibility to the aperture 17 when registered therewith, so that any accumulations may be easily and readily removed through said outlet 11.

Should the discharge passage 6 become clogged, the plug 8 may be removed, thereby giving access to said passage when the aperture 17 is registered therewith, whereby any accumulation may be readily removed therefrom.

I have also provided the inner end of the valve 12 with a reduced projection 23 on the inner end thereof, which engages a similar projection cast or otherwise formed on the inner end or wall of the valve casing 9, in order to limit the inward movement of the said valve 12, and at the same time leave a space between the inner end of said valve 12 and the casing 9 when the aperture 17 of said valve is in register with the outlet 11 of the casing 9.

Similarly, a chamber is formed on the opposite or outer end of the valve 12, when in its outermost position with its aperture 17 in registration with the discharge passage 6, by means of the cap 21. Both chambers thus produced are provided with suitable vents 26. As the plunger or valve 12 is reciprocated, should any small quantity of the commodity being dispensed find its way between said valve 12 and the walls of the casing 9, such matter will eventually be pushed, by the blunt ends of the valve 12, into one or the other of the chambers thus formed and eventually such matter will be pushed out of said chambers, and casing 9, thereby making the device automatically self-cleaning.

Having thus described my invention, what I claim as new and desire to secure by Letters Patent is—

1. A dispensing device comprising a receptacle having a vertically disposed discharge passage intersected by a valve casing and an outlet extending downwardly from said cas-

ing and offset from said discharge passage; detachable means for closing the bottom of said discharge passage below the valve casing whereby said passage may be rendered accessible for cleaning by removal of said closing means; a reciprocable valve mounted within said casing and having a vertically disposed aperture registerable with either the discharge passage or the outlet; resilient means for normally urging said valve to register with the discharge passage; and adjustable means for limiting the movement of said valve when urged by said resilient means whereby said aperture within said valve may normally register with the discharge passage to receive a charge of the contents of said dispensing means.

2. A dispensing device comprising a receptacle having a vertically disposed discharge passage intersected by a valve casing, and an outlet extending downwardly from said casing and offset from said discharge passage; detachable means for closing the bottom of said discharge passage below the valve casing whereby said passage may be rendered accessible for cleaning by removal of said closing means; a reciprocable valve mounted within said casing and having a vertically disposed aperture registerable with either the discharge passage or the outlet; resilient means for normally urging said valve to register with the discharge passage; adjustable means for limiting the movement of said valve when urged by said resilient means whereby said aperture within said valve may normally register with the discharge passage to receive a charge of the contents of said dispensing means; and means for moving said valve to register the aperture therein with the outlet.

3. A dispensing device comprising a receptacle having a vertically disposed discharge passage intersected by a valve casing, and an outlet extending downwardly from said casing and offset from said discharge passage; detachable means for closing the bottom of said discharge passage below the valve casing whereby said passage may be rendered accessible for cleaning by removal of said closing means; a reciprocable valve mounted within said casing and having a vertically disposed aperture registerable with either the discharge passage or the outlet; resilient means for normally urging said valve to register with the discharge passage; adjustable means for limiting the movement of said valve when urged by said resilient means whereby said aperture within said valve may normally register with the discharge passage to receive a charge of the contents of said dispensing means; and means for preventing rotation of the valve within the casing.

4. A dispensing device comprising a receptacle having a vertically disposed discharge passage intersected by a valve casing, and an

outlet extending downwardly from said casing and offset from said discharge passage; detachable means for closing the bottom of said discharge passage below the valve casing whereby said passage may be rendered accessible for cleaning by removal of said closing means; a reciprocable valve mounted within said casing and having a vertically disposed aperture registerable with either the discharge passage or the outlet; resilient means for normally urging said valve to register with the discharge passage; adjustable means for limiting the movement of said valve when urged by said resilient means whereby said aperture within said valve may normally register with the discharge passage to receive a charge of the contents of said dispensing means; and means for preventing rotation of the valve within the casing, said casing having chambers provided with vents formed in each end thereof to receive and discharge matter moved thereinto by the valve.

5. A dispensing device comprising a receptacle having a vertically disposed discharge passage intersected by a valve casing and also having an outlet extending downwardly from said casing and parallel to, but offset from, said intersected passage; a reciprocal valve mounted within said valve casing and having a vertically disposed aperture registerable with either said discharge passage or outlet; means for normally urging said valve to register the aperture therein with said discharge passage; and detachable means mounted within the end of the discharge passage below the valve casing to close said passage and whereby said passage may be rendered accessible for cleaning the same and the valve aperture registered therewith.

40 6. A dispensing device comprising a receptacle having a vertically disposed discharge passage intersected by a valve casing and also having an outlet extending downwardly from said valve casing and parallel to, and offset from, said discharge passage; a valve slidably mounted within said valve casing and having an aperture therein, said valve being normally positioned to register the aperture with the discharge passage of said dispenser and movable within said valve casing to register said aperture with said outlet; and detachable means closing the end of the discharge passage below said intersecting valve casing whereby said passage and valve aperture registered therewith may be rendered accessible for cleansing and other purposes.

65 7. A dispensing device comprising a receptacle having a vertically disposed discharge passage intersected by a valve casing and also having an outlet extending downwardly from said valve casing and parallel to, and offset from, said discharge passage; a valve slidably mounted within said valve casing and having an aperture therein, said valve being normally positioned to register the aper-

ture with the discharge passage of said dispenser and movable within said valve casing to register said aperture with said outlet; and a detachable plug normally closing the end of the discharge passage below said intersecting valve casing, whereby access to said passage and the valve aperture registered therewith may be had for cleansing and other purposes when said plug is removed.

In witness whereof, I hereunto set my signature.
